UNITED STATES PATENT OFFICE.

ROBERT W. SCOTT, OF LEEDS POINT, NEW JERSEY, ASSIGNOR OF ONE-HALF
TO LOUIS N. D. WILLIAMS, OF OGONTZ, PENNSYLVANIA.

RIBBED KNITTED FABRIC.

No. 846,429.

Specification of Letters Patent.

Patented March 5, 1907.

Application filed August 17, 1906. Serial No. 331,014.

To all whom it may concern:

Be it known that I, ROBERT W. SCOTT, a citizen of the United States, residing in Leeds Point, Atlantic county, New Jersey, have invented certain Improvements in Ribbed Knitted Fabrics, of which the following is a specification.

My invention relates to that class of knitted fabrics in which ornamental open-work effects are produced by the formation of eyelet-holes in a knitted web, one of the objects of my invention being to produce such ornamental or open-work effects in ribbed webs without transferring stitches from one needle-wale to another, and a further object being to enlarge the size of the eyelet-hole beyond the normal in that class of webs in which the eyelet-hole is formed by the lateral displacement of a sinker-wale.

20 The figure in the accompanying drawing is an exaggerated view of a piece of ribbed knitted web illustrating the manner of forming eyelet-holes in the same in accordance with my invention.

25 In the drawing, *a a* represent the wales of one face of the fabric—say, for instance, those produced by the cylinder-needles of a rib-knitting machine. *b b* represent the wales of the other face of the fabric—say, for instance, those produced by the dial-needles of the machine—and *d d* represent the sinker-wales or those portions of the knitting-yarn passing from one needle-wale to the other.

35 In order to produce an eyelet-hole in the web, I displace the sinker-wale yarn at the point where the eyelet-hole is to be produced and cause it to engage with an adjoining wale of either face of the fabric. Thus, as shown 40 at *e*, the displaced sinker-wale engages with a cylinder-wale of the fabric, and, as shown at *f*, the displaced sinker-wale engages with a dial needle-wale of the web, or the displaced sinker-wale may be spread laterally in both 45 directions, so as to engage both with a cylinder needle-wale and with a dial needle-wale, as shown at *g*. In order to enlarge the eyelet-hole beyond the size normally due to the displacement of the sinker-wale, I prefer in 50 some cases to slacken the sinker-wale of the preceding course—as shown, for instance, at *i*.

Where a still larger eyelet-hole is desired, the sinker-wale yarn in a plurality of adjoining courses may be displaced and caused to engage with either one or both of the adjoining 55 needle-wales, as shown—for instance, at *m* and *n*, respectively—this double displacement being also, if desired, combined with the slackening of the sinker-wale of the preceding course.

60 In order to effect the desired results, an ordinary rib-knitting machine may be provided, either in the cylinder or dial, with supplementary needles, bars, or points for engaging the yarn of the sinker-wales, said yarn 65 being either displaced from its normal path from needle to needle, in order to slacken it, or being transferred laterally to a needle of either or both members of the machine when it is to engage a needle-wale of one or both 70 faces.

I claim—

1. A ribbed, knitted web having eyelet-holes therein, each formed by the laterally-displaced yarn of a sinker-wale engaging an 75 adjoining needle-wale of said ribbed fabric.

2. A knitted web having eyelet-holes therein, each formed by the laterally-displaced yarn of a sinker-wale engaging an adjoining needle-wale, and by a slackened 80 sinker-wale of a preceding course.

3. A ribbed, knitted web having eyelet-holes therein, each produced by the laterally-displaced yarn of a sinker-wale engaging adjoining needle-wales of both faces of the web. 85

4. A ribbed, knitted web having eyelet-holes therein, each produced by the laterally-displaced yarn of a sinker-wale engaging adjoining needle-wales of both faces of the web and by a slackened sinker-wale of a preceding 90 course.

5. A ribbed, knitted web having eyelet-holes therein, each produced by the laterally-displaced yarns in a plurality of adjoining courses of a sinker-wale engaging with an adjoining needle-wale.

6. A ribbed, knitted web having eyelet-holes therein, each produced by the laterally-displaced yarns in a plurality of adjoining courses of a sinker-wale engaging with an adjoining needle-wale and by a slackened sinker-wale of a preceding course.

7. A ribbed, knitted web having therein eyelet-holes, each produced by the laterally-displaced yarns in a plurality of adjoining courses of a sinker-wale engaging adjoining 5 needle-wales of both faces of the web.

8. A ribbed, knitted web having therein eyelet-holes, each produced by the laterally-displaced yarns in a plurality of adjoining courses of a sinker-wale engaging adjoining

needle-wales of both faces of the web and by 10 a slackened sinker-wale of a preceding course.

In testimony whereof I have signed my name to this specification in the presence of two subscribing witnesses.

ROBERT W. SCOTT,

Witnesses:

HAMILTON D. TURNER,

KATE A. BEADLE.
